SATELLITE LAUNCHING TOY

Dean R. Thorson, Broderick, Calif., assignor of one-fourth to Ambrose M. Bertsch, and one-fourth to Everett W. Sharp, both of Broderick, Calif.

Filed Feb. 18, 1963, Ser. No. 73,598

Term of patent 14 years

(Cl. D34—15)

Fig. 1.

Des. 195,860

PAGE 2

Fig. 2.

Fig. 3.

FIG. 1 is a front perspective view of a satellite launching toy, showing my new design;

FIG. 2 is a bottom rear perspective view thereof; and
FIG. 3 is a side elevational view.

I claim:

The ornamental design for a satellite launching toy, as shown.
